VIBRATING SCREEN

Theodore B. Hetzel, West Chester, Pa., assignor
to Link-Belt Company, Chicago, Ill., a corpora-
tion of Illinois

Application July 16, 1931. Serial No. 551,073

7 Claims. (Cl. 209—326)

This invention relates to improvements in vibrating screen structures.

One of the objects of this invention involves a novel combination of supporting screen box, 5 eccentric drive for the screen box, and long leaf springs interconnecting the screen box and the support.

A further object of this invention is the provision of an association of these elements for the purpose of securing a screen action which is uniform, steady, and of considerable intensity.

10 A further object of this invention involves the interconnection of the screen box and support by means of leaved springs terminating in spiral spring connections for modifying the normally circular movement of the screen surface into a more or less elliptical movement.

These and other objects, as will appear from the following disclosure, are secured by means 20 of this invention.

This invention resides substantially in the combination, construction, arrangement, and relative location of parts, all as will be described in greater detail below.

25 Referring to the drawings—

Figure 1 is a side elevational view of the screen of this invention;

Fig. 2 is an enlarged detail cross-sectional view, taken on the line 2—2 of Fig. 1;

30 Fig. 3 is a vertical central cross-sectional view through one of the bearing supports and one of the driving eccentrics; and

Fig. 4 is a side elevational view of a modified form of screen employing this invention.

35 The structure of this invention comprises a supporting frame 1 of any suitable form and shape made preferably of steel channel beams cross braced in any suitable manner. Mounted on the sides of this frame are bearing supports 2 in which a shaft 3 is journaled. The shaft is provided at one end with a driving pulley 4, or other suitable driving connection. Mounted on this shaft by means of the bearing housing shown generally at 6 is the screen box 5. This screen 40 box has not been shown in detail since it may be of many known forms of construction and, of course, includes in the bottom thereof a suitable screen cloth or wire secured in place by any one of a number of well known tensioning devices. Mounted on the shaft are two unbalanced pulleys shown at 7. Depending from the under surface of the screen box near each end thereof, and on each side thereof, are the brackets 8 provided with pintles 9. A long compound leaf spring 10 is secured near the center to a supporting bracket 12 which is provided with an arcuate slot 13. Secured to the cross braces 17 is an anchoring plate 16 mounted so as to be adjacent the bracket 12. 55 A suitable fastening nut and bolt 14 pass through

the plate 16 and the slot 13 of the plate 12 so that the bracket 12 may be secured in any one of a number of different positions with respect to the fixed plate 16. An opening 15 in the side frame of the support permits of access to the nut and bolt 14. The ends of the upper leaf of the compound spring 10 terminate in spiral springs 11 which are secured at their centers to the pintles 9. As is clear from Fig. 1, and the construction described above, the screen box 65 may be adjusted to any one of a number of inclined positions with respect to the horizontal between predetermined limits.

Fig. 2 shows the relationship of the supporting frame, cross braces, bracket 12, plate 16, 70 and the fastening nut and bolt 14.

75 The details of construction are shown in Fig. 3. The shaft 3, of course, extends between the sides of the supporting frame 1 and is provided with eccentric portions 20 of reduced diameter. As shown in Fig. 3 the center line of the concentric portion of the shaft is shown at A. The center line of the eccentric portion 20 is shown at B. The eccentricity therefor is 80 represented by the distance between the lines A and B. The shaft 3 is provided with a second reduced concentric portion 19 which is journaled in the bearing 2. This portion is provided with a bearing sleeve 21 upon which is mounted an inner roller race 22. Surrounding this inner roller race is an outer roller race 23 which is mounted in the bearing 2 between the parts 24 and 26 thereof, which forms an enclosed casing. This enclosed casing is mounted on a suitable support 25 by means of which 85 it may be attached to the side frames 1. The reduced portion 18 of shaft 3 extends through this casing and is provided with a pulley or other suitable driving connection 4. The unbalanced flywheel 7 is shown provided with a weight 28 which may be circumferentially adjusted and then locked in place. The eccentric casing, shown generally at 6, comprises a shell 29 closed by means of a cover plate 30 and within which is mounted an outer roller race 32. 90 Mounted within the outer roller race is an inner roller race 31 which surrounds the eccentric portion 20 of the shaft 3. Extending between the eccentric housings 6 is a cylindrical casing 33 which entirely encloses the shaft 3 so that it is protected from the intrusion of dirt, sand, and other foreign materials. It is, of course, apparent that the portions 18, 19 and the central concentric portion of the shaft 3 are all on the same central axis and that the eccentric portion 20 is cylindrical and formed about the axis B which is displaced a slight distance from the main axis A. Thus, as the shaft revolves, the screen frame and eccentric 95 housings would travel in a small circular path 100 105 110 115 120

determined by the eccentricity of the eccentric portion 20.

This circular movement of the screen frame and the cloth mounted therein is modified into 5 an elliptical movement by reason of the long compound leaf springs 10 which interconnect the screen frame with the supporting base. This modification of the normal action of the screen driven by an eccentric is further attained by 10 reason of the fact that the transverse supporting shaft 3 is mounted outside of and spaced from the center of gravity of the screen box. It will, of course, be apparent that although this shaft is shown mounted below the center of gravity, 15 the structure may be modified within the scope of this invention so that it is mounted above the center of gravity. It is hardly necessary to point out that the weighted pulley is mounted in relation to the eccentric so that 20 they counterbalance each other insuring smoother operation.

By mounting the shaft 3 away from the center of gravity of the screen box the eccentric drive shaft effects greater unbalanced kinetic 25 forces to provide a uniform, intense screening action. The inter-position of the leaf springs in the manner shown causes the particles on the screen cloth to describe elliptical paths of such size and direction that the action on the 30 material passing over the screen is most effective. Experience with a screen of this nature has demonstrated that at the receiving end of the screen the tendency is for a retardation and quick screening of the material thereon, while 35 at the discharge end the motion assists the oversized particles to leave the screening surface rapidly.

A modified form of structure is shown in Fig. 4 employing the principles of this invention. At 40 are the supporting standards which are provided at their top with arcuate surfaces upon which complementary supporting members 41 are mounted and secured thereto in any one of a number of different angular positions by fastening means 42. The bearing housings 47 are mounted on the supports 41 and have journaled in them a transverse shaft 48 which is connected to the screen box 44 by means of eccentrics and eccentric housings, as previously described. The 45 shaft 48 is provided with a suitable driving member 49. As before, an unbalanced pulley 50 is mounted on the shaft 48. The long compound leaf springs 43 are secured to the support 41 near their center and terminate as before in spiral springs 46 which are attached to the ends of the screen box by means of brackets 55 45.

It should be noted here that if desired the spiral springs 46 instead of extending upwardly 60 could just as well extend downwardly without departing from this invention. The operation of this form of screen structure is substantially the same as that described in connection with Figs. 1 to 3 inclusive.

From the above description it will be apparent 65 that this invention resides in certain principles of construction and operation which may be set forth in other physical forms and I do not, therefore, desire to be strictly limited to the disclosure as given for purposes of illustration but rather to the scope of the appended claims.

What I seek to secure by United States Letters Patent is:

1. A vibrating screen of the type described comprising a supporting frame, a screen box, a shaft journaled on the frame, eccentric driving connections between the screen box and the shaft, compound leaf springs terminating in involute curved springs, means for securing the leaf springs near their center to the supporting frame, and means for attaching the involute coiled ends of the leaf springs to the screen box. 80

2. A vibrating screen of the type described comprising a supporting base, a screen box, a shaft journaled on the base, eccentric driving connections between the shaft and the screen box, long leaf springs secured to the supporting base, said leaf springs terminating at their ends in coiled springs, and means for connecting the centers of the coiled springs with the screen box. 85

3. A vibrating screen of the type described comprising a supporting base, a screen box, a shaft journaled on the base, eccentric driving connections between the shaft and the screen box, long leaf springs secured to the supporting base, said leaf springs terminating at their ends in coiled springs, means for connecting the centers 90 of the coiled springs with the screen box, and counter balancing means mounted on said shaft. 95

4. A vibrating screen of the type described comprising a supporting base, a shaft journaled on said base, a screen box supported on said shaft by eccentric driving means, a compound leaf spring terminating at each end in coiled springs, means for securing the coiled springs at their inner ends to the screen box, and adjustable means for securing the leaf springs near 100 their center to the supporting base, whereby the screen box may be inclined at different angles to the horizontal. 105

5. A vibrating screen of the type described comprising a supporting frame, a screen box, eccentric driving means for supporting the screen 115 box on the frame and for vibrating it, long leaf springs terminating in involute spring coils secured to the supporting frame, and means for attaching the coiled ends of the springs to the 120 screen box. 125

6. A vibrating screen of the type described comprising a supporting frame, a transverse shaft journaled on said frame and having spaced eccentrics formed thereon, a screen box, means 130 for attaching the screen box to the transverse shaft at the eccentrics, long compound leaf springs terminating in spirally coiled ends, means for attaching the leaf springs to the supporting frame, an unbalanced weighted pulley secured to 135 said shaft and pintled brackets interconnecting the screen box and the centers of the coiled ends of the leaf springs. 140

7. A vibrating screen of the type described, comprising a supporting frame, a screen box, a shaft journaled on the frame, eccentric driving connections between the screen box and the shaft, longitudinal members terminating in coiled springs at each end, means for anchoring 145 said members at their centers, means for attaching the coiled spring to the screen box and said screen box longitudinal members, means for anchoring said members at their centers being angularly adjusted about said shaft and means for securing them in various angular positions. 150
